UNITED STATES PATENT OFFICE.

FREDERICK J. MOTZ, OF NEW YORK, N. Y.

MACHINE FOR MAKING PAPER ARTICLES.

SPECIFICATION forming part of Letters Patent No. 795,153, dated July 18, 1905.

Application filed May 21, 1904. Serial No. 209,048.

To all whom it may concern:

Be it known that I, FREDERICK J. MOTZ, a citizen of the United States, and a resident of the city of New York, borough of Manhattan, in the county of New York and State of New York, have invented a new and Improved Machine for Making Paper Articles, of which the following is a full, clear, and exact description.

My invention resides in a certain novel machine by which seamless paper articles may be produced, the machine being of that form having a vat and means for automatically submerging foraminous shapes therein and withdrawing them therefrom and exerting through the shapes a fluid movement during the time of their submergence, thus causing the pulp to adhere to the shapes, so that after they are withdrawn from the vat the pulp may be allowed to harden or set on the shapes to form the finished articles.

I will now specifically describe the preferred embodiment of my invention, reference being had to the accompanying drawings, forming a part of this specification, in which—

25 Figure 1 is a longitudinal section of the machine. Fig. 2 is a cross-section thereof. Fig. 3 is an enlarged sectional view of one of the suction-heads, showing one of the shapes engaged therewith and illustrating the automatic action of the suction-cut-off valve. Fig. 4 is a detail perspective view showing the preferred manner of forming the shape and illustrating the manner in which the pulp accumulates thereon, and Fig. 5 is a detail of one of the spring-closed valves.

10 indicates a vat for containing the pulp, which is supplied to the upper part of one end thereof through a pipe or conduit 11. In said vat is arranged a horizontal partition 12, forming a false bottom and having at each end a vertical partition 14. Said partitions 12 and 14 are in water-tight engagement with the sides of the vat and form, therefore, a continual or endless passage through which the pulp may be circulated in the manner indicated by the arrows in Fig. 1. 15 indicates any desired form of pump—for instance, a fan-pump—for maintaining this continual circulation of the pulp, by which means the pulp 50 is kept at an even consistency and the solid

parts thereof prevented from settling in the bottom of the vat.

16 indicates a plug or equivalent connection for draining the vat.

Mounted on the sides of the vat are boxes 55 17, in which are mounted to turn the journals 18 of a suction-drum 19.

20 indicates a suction-pipe extending through one of the trunnions 18, which is hollowed for this purpose and projects downward into the suction-drum. Said pipe 20 is adapted to have communication with any suitable vacuum-forming apparatus, so as to exert a continual suction within the drum 19. The remaining or solid journal 18 of the drum 19 65 has fastened thereto a pulley 21, by which means or by any other means suitable for this purpose a continual rotary movement may be given to the drum. As here shown, the pump 15 is driven also by a belt connection 22 70 from the said remaining journal of the suction-drum 19.

Communicating with the interior of the suction-drum 19 and passing radially therefrom are a number of stout tubes 23, each provided with a valve 24, having a spring 24^a or other suitable means for normally holding them closed. (See Fig. 5.) The valves 24 also have operating fingers or handles 25, in the path of which is arranged a segmental track 80 26, suitably supported at one side of the tubes 23 by any desired means—for example, by the rods 26^a. (Best shown in Fig. 2.) One end of the track 26^a is located just above the upper edge of the vat 10, while the opposite end is 85 located some distance above the top of the vat. The drum 19, with its attachments, is intended to turn toward the first-named end of the track, as indicated by the arrow in Fig. 1, and the result, therefore, of the peculiar 90 arrangement of the track and its relation to the operating fingers or handles 25 of the valves 24 is that as the tubes 23 dip into the vat the handles 25 strike the low end of the track 26, and the valves 24 are automatically 95 opened, allowing the suction within the drum 19 to be exerted through the pipes 23. This condition continues as the tubes move through the vat and until the tubes rise above the vat sufficiently to clear the operating arms or han- 100

dles 25 of the valves 24 from engagement with the second-named or high end of the track. The special advantage of this operation will be set forth hereinafter.

5 Each suction-tube 23 carries at its outer end a suction-head 27. These heads are, according to the form of the invention here illustrated, essentially pan-shaped and provided with broad edges or marginal faces 28. (Shown best in Figs. 2 and 3.) The outer ends of the tubes 23 at the points where they open into the suction-heads 27 are commanded by sliding cut-offs 29. Said cut-offs are connected to stems 30, and the stems have springs 31, applied so as to keep the cut-offs normally active. The inner ends of the stems 30 are turned laterally, as indicated at 32, and project through openings 33 in the faces 28 of the suction-heads, so that when the shapes are placed in 10 position on the suction-heads, as will be hereinafter fully stated, the cut-offs 29 will be automatically moved to open or inactive position. In order to strengthen the machine and also to assist in holding the shapes in position, 15 I provide two annular bands 33^a, fastened suitably to the side edges of the suction-heads 27 and formed with radial slots 34, the slots lying respectively in transverse line with the faces 28 of the suction-heads 27.

20 The shapes or forms may be of any size and contour desired, this being dependent upon the shape of the article to be formed, and a number of shapes of different sizes and forms may be used in the machine at the same time.

25 As here illustrated, each of the shapes comprises a framing made up of a relatively coarse wire mesh 35, with a binding 36 of wire or the like. Over said mesh is arranged a finer screen 37, of suitable metal, the screen 37 being that on which the paper article is formed 30 and its shape being that which it is desired to give said article.

In Fig. 4, *a* may be taken to indicate the pulp as it gathers on the screen 37 during the 45 formation of the article within the vat. Each shape is also provided at its upper side with a hook 38, adapted to engage over the outer edge of the suction-head to which the shape is applied, thus holding the shape in position. The shapes are also provided with laterally-projecting studs 39, which may, if desired, be formed as continuations of the bottom binding-bar 36, the said projections 39 being adapted to engage in the slots 34 of the bands 50 or plates 33^a, thus guiding the movements of the shapes when engaging with and disengaging from the machine and assisting in holding the shapes properly in position. Reference to Fig. 3 will show the relative position of the 55 shapes and suction-heads when in operation, from which it will be seen that the hooks 38 engage the outer ends of the suction-heads, while the inner portion of the binding 36 of the shape engages the projected part 32 of the valve- 60 stem 30, thus moving the cut-off valve 39 to

inactive position, as explained. This movement of the cut-off takes place the instant that the shape is inserted into the machine, and a closing movement takes place by the operation of the spring 31 the instant that the shape is removed from the machine. It will also be observed that the binding 36 or the edge of the shape bears around the broad face 28 of the suction-head, forming an essentially hermetic connection therewith, the effectiveness whereof is increased immediately after the inception of the operation by the accumulation of pulp around the edges of the shape. 70 75 80 85 90 95 100 105 110 115 120 125 130

In the organized operation of the machine the shapes are introduced between the right-hand ends of the guides, (assuming that the wheel is turning in the direction indicated by the arrow in Fig. 1,) with the projections 39 engaged in the grooves in the guides. The shapes will drop down between the guides until the projections 39 enter two of the slots 34, whereupon the shapes will move with the wheel and will be simultaneously run downward between the guides until the concentric portions of the guides are reached by the projections 39, whereupon the hooks 38 will engage the outer ends of the suction-heads, and this, together with the engagement between the projections 39 and the inner end of the slots 34, will arrest further independent movement of the shapes. As the shapes take this position they engage the parts 32 of the stems 30 and automatically open the cut-offs 29. It should be noted that suction cannot be exerted through the heads 27 until the valves 24, corresponding with the heads, are opened. The rotation of the wheel is continued until the shape is submerged in the vat, and at this period the handle 25 of the valve 24, corresponding to the said shape, strikes the track 26, and said valve 24 is opened. Suction is then exerted through the head 27, tube 23, and drum 19, and the water is drawn through 130

the foraminous shape, this current causing the solid parts of the fiber to cling to the foraminous shape and form a covering of a size and form corresponding to that of the shape. The shape continues this movement through the vat and finally rises at the other side. It should be observed, however, that the suction is not cut off until the valve-handles 25 disengage the high end of the track 26. 5 This allows a certain period during which atmospheric air is drawn by suction through the shape and layer of pulp thereon, thus effectively withdrawing from the pulp all surplus liquid and leaving the pulp relatively solid on the shape. When the high end of the track 26 is left by the valve-handles 25, the projections 39 of the shape begin to run into the second eccentric or tangential ends of the guides and are thereby caused to move outward until finally they are completely disengaged from the wheel, as Fig. 1 illustrates. At this time 10 the cut-off 29 will be allowed to become active, and the suction-pipe 23, corresponding to the shape thus moved out of engagement with the suction-head, will be closed. In connection with this cut-off device it will be seen that while the valves 24 actually control the beginning and end of the suction period the valves or cut-offs 29 prevent breaking 15 the partial vacuum or sucking the pulp into the suction-drum 19 should one of the shapes miss its position in the machine or should it become displaced therein. The shape with the pulp clinging thereto, as explained, 20 should now be dried and the pulp allowed to set, thus forming a finished seamless paper article corresponding accurately to the shape on which it was produced. The pulp which is run into the vat is beaten and prepared in 25 the manner usual for paper-making and is then further mixed with water to a density of approximately two to three parts of pulp to one thousand parts of water. The flow of the pulp into the vat should be regulated so 30 as to keep the level of the mixture therein close to the upper edge of the vat.

I provide means for automatically taking the shapes with the pulp clinging thereto from the machine, transporting the shapes to a suitable means for artificially drying the pulp and for disengaging the finished paper articles from the shapes and then returning the latter into the machine, thus allowing the operation of forming the paper articles to go on 35 continuously and avoiding the necessity of manually handling either the shapes or the paper articles during the period of formation. According to the form of the invention illustrated in the drawings this means for automatically handling the shapes comprise an endless carrier running over the top of the superstructure 40 and formed of two endless chains 42 with transverse rods 43 pivotally mounted on the links thereof. Said rods are 40 provided with hooks 44, adapted to engage in

openings 38^a, formed in the hooks 38. The hooks 44 are also provided with projecting fingers 45, adapted at a certain point in the path of the carrier to strike a wedge-like detent 46, thus throwing back the hooks 44 and 45 allowing them to disengage from the walls in the orifices 38^a. As the carrier moves in the manner indicated in Fig. 1 its hooks 44 successively engage in the orifices 38^a of the shapes as they are successively raised from the wheel by the eccentric or tangential form of the guides 41. The shapes with the pulp adhered thereto are then moved by the carrier into the drying-room or other means for artificially drying the pulp. The carrier 50 moves continuously through the drying-room, and the arrangement is such that when the upper run of the carrier passes from the drying room or apparatus the pulp will be set or hardened, thus forming the finished seamless article. At a suitable point a blower 47 is located, which causes a blast of air to be forced through the foraminous shape and to impinge against the finished article thereon, thus blowing the article from the shape and completing 55 the operations on the article. The carrier in continuing its movement advances the shapes into position to re-enter the machine, and at this point the finger 45 strikes the said detent 46 and causes the hook 44 to rock backward, 60 thus automatically releasing the shape. Various other devices may be provided for automatically removing the shapes from and engaging them with the machine, and in this connection I would mention that the shapes 65 may be attached either permanently or removably to a carrier chain or chains which are preferably endless and which are run with the shapes through the guides 41, these chains, therefore, moving the shapes continuously 70 through the machine out to the drying-room or other drying means and thence back into the machine, thus maintaining continuous operation and insuring rapid work.

Having thus described the preferred embodiment of my invention, I claim as new and desire to secure by Letters Patent—

1. In a machine for making paper articles, the combination of a vat, a suction-head, means for mounting the same to move it in and out of the vat, a foraminous shape adapted to engage the suction-head, a valve controlling communication between the suction-head and the suction source, and means for operating the valve by the movement of the foraminous shape into position on the suction-head.

2. In a machine for making paper articles, the combination of a vat, a suction-head, means for mounting the suction-head to move in and out of the vat, means controlling communication between the suction-head and the suction source, an operating device for said means, the operating device acting to open said communication upon the entry of the suction-head into the vat, and to close said communication

upon the exit of the suction-head from the vat, and a foraminous shape adapted to engage the suction-head.

3. In a machine for making paper articles, the combination of a vat, a revolubly-mounted suction-drum located over the same, a suction-head, a suction-tube establishing communication between the head and drum, a foraminous shape adapted to engage the suction-head, a valve commanding the suction-tube, and a track arranged to hold the valve in open position, said track being broken to allow the valve to close when the suction-heads are out of the vat.

15 4. In a machine for making paper articles, the combination of a vat, a suction-head, means for revolubly mounting the suction-head to dip into the vat, said means including a side member having a radial slot, a stationary 20 guide located alongside of the said side member, and a foraminous shape adapted to engage the suction-head and having a part running in said slot and guide.

5. In a machine for making paper articles, the combination of a vat, a suction-head, means for revolubly mounting the suction-head to dip into the vat, said means including a side member having a radial slot, a stationary 25 guide located alongside of the said side member, and a foraminous shape adapted to engage the suction-head and having a part running in said slot and guide, the guide having a part concentric to the center of revolution of the suction-head, and a part eccentric 30 thereto for the purpose specified.

6. In a machine for making paper articles, the combination of a vat, a suction-head, means for revolubly mounting the suction-head to dip into the vat, said means including a side 40 member having a radial slot, a stationary guide located alongside of the said side member, and a foraminous shape adapted to engage the suction-head and having a part running in said slot and guide, the guide having 45 its middle portion concentric to the center of revolution of the suction-head and having its end portions passing outward eccentrically to said center of revolution for the purpose specified.

50 7. In a machine for making paper articles, the combination of a vat adapted to contain paper-pulp, a foraminous form, means for moving said form in and out of said vat and to communicate to the form a sucking effort, 55 a valve commanding said means for communicating said sucking effort, and a track located in the path of a part of the valve to be engaged by said part during the time that the form is submerged in the pulp whereby to 60 open the valve.

8. In a machine for making paper articles, the combination of a vat adapted to contain paper-pulp, a foraminous form, means for moving said form in and out of said vat, and 65 for communicating a sucking effort to said

form, a valve commanding said means for communicating said sucking effort, and a track located in the vat in the path of a part of the valve to be engaged by said part during the time that the form is submerged in the pulp 70 whereby to open the valve.

9. In a machine for making articles from paper-pulp, the combination of a suction-head adapted to be submerged in the pulp, a valve commanding the same, and a foraminous form 75 adapted to be removably placed on and submerged with the suction-head and capable of actuating said valve to open same when the form is placed in position.

10. In a machine for making articles from paper-pulp, the combination of a suction-head adapted to be submerged in the pulp and having a suction-orifice therein, a sliding valve commanding said orifice, a stem attached to the valve, a spring actuating the valve to close 85 the same, and a foraminous form adapted to be placed on and submerged with the suction-head and to engage said stem to open the valve when the form is placed in position.

11. In a machine for making articles from paper-pulp, the combination of a suction-head adapted to be submerged in the pulp and having a suction-orifice, a valve commanding the orifice, the valve having a part projecting therefrom, means tending to seat the valve, 95 and a foraminous form adapted to be removably placed on and submerged with the suction-head and to engage the said projecting part of the valve to open the valve when the form is placed in position. 100

12. In a machine for making paper articles, the combination of a vat adapted to contain paper-pulp, a suction-drum revolubly mounted on the vat, means for exerting a sucking effort within the drum, a tubular arm projecting from and communicating with the drum, a suction-head attached to the arm, and communicating with the interior thereof, and a foraminous form adapted removably to engage the suction-head. 110

13. In a machine for making paper articles, the combination of a vat adapted to contain paper-pulp, a suction-drum revolubly mounted on the vat, means for exerting a sucking effort within the drum, a tubular arm projecting from and communicating with the drum, a suction-head attached to the arm and communicating with the interior thereof, a foraminous form adapted removably to engage the suction-head, and means for automatically 115 engaging the form with and disengaging it from said head. 120

14. In a machine for making paper articles, the combination of a vat adapted to contain paper-pulp, a suction-drum revolubly mounted on the vat, means for exerting a sucking effort within the drum, a tubular arm projecting from and communicating with the drum, a suction-head attached to the arm and communicating with the interior thereof, a fo- 125

5 raminous form adapted removably to engage the suction-head, a valve commanding said tubular arm, and means for automatically opening said valve during the time that the suction-head is submerged in the pulp.

15. In a machine for making paper articles, the combination of a vat adapted to contain paper-pulp, a suction-drum revolvably mounted on the vat, means for exerting a sucking effort within the drum, a tubular arm projecting from and communicating with the drum, a suction-head attached to the arm and communicating with the interior thereof, a foraminous form adapted removably to engage the suction-head, a valve commanding said tubular arm, means tending normally to close the valve, and a track adapted to be engaged by a part of the valve to open said valve during the time that the suction-head is submerged in the pulp.

20 16. In a machine for making paper articles, the combination of means for supplying pulp, a separate form, a rotating means having a radial guide adapted to be engaged by a part 25 of the form, and a relatively stationary eccentric guide also adapted to be engaged by a part of the form.

25 17. In a machine for making paper articles, the combination of means for supplying pulp, a separate form, a rotating means having a radial guide adapted to be engaged by a part 30 of the form, a relatively stationary eccentric guide also adapted to be engaged by a part of the form, and devices for automatically delivering the form to and from the said rotating means and eccentric guide.

35 18. In a machine for forming paper articles, the combination of a vat, a separate form, a rotating means adapted removably to carry the form and to move the same in and out of the vat, said rotating means having a radial guide adapted to be slidably engaged by a part of the form, and a relatively stationary eccentric guide also adapted to be engaged by a part of the form.

40 19. In a machine for forming paper articles, the combination of a vat, a separate form, a rotating means adapted removably to carry the form and to move the same in and out of the vat, said rotating means having a radial guide adapted to be slidably engaged by a part of the form, a relatively stationary eccentric guide also adapted to be engaged by a part of the form, and devices for automatically engaging the form with and disengaging the form from said rotating means and said eccentric guides.

45 20. A machine for forming paper articles comprising a vat, a revolvably-mounted suction-head adapted to move in and out of the vat, a radially-slotted member juxtaposed to the suction-head, and a form adapted to cover the suction-head and having a part fitting in the slot of the said member.

50 21. A machine for forming paper articles

comprising a vat, a revolvably-mounted suction-head adapted to move in and out of the vat, a radially-slotted member juxtaposed to the suction-head, a form adapted to cover the suction-head and having a part fitting in the slot of the said member, and a relatively stationary eccentric guide juxtaposed to said slotted member and also adapted to be engaged by a part of the form.

55 22. In a machine for forming paper articles, the combination of a vat, a revolvably-mounted suction-head adapted to move in and out of the vat, a radially-slotted member juxtaposed to and moving with the suction-head, a relatively stationary guide having a part concentric to the center of movement of the suction-head and having its ends running off eccentrically thereto, and a form adapted to cover the suction-head and adapted to engage the walls of said slot in the slotted member and said guide.

60 23. In a machine for forming paper articles, the combination of a vat, a revolvably-mounted suction-head adapted to move in and out of the vat, a radially-slotted member juxtaposed to and moving with the suction-head, a relatively stationary guide having a part concentric to the center of movement of the suction-head and having its ends running off eccentrically thereto, a form adapted to cover the suction-head and adapted to engage the walls of said slot in the slotted member and said guide, and devices for automatically delivering the form to and receiving the form from said slotted member and guide.

65 24. In a machine for forming paper articles, the combination of a vat, a suction-head revolvably mounted to move in and out of the vat, a valve controlling the suction through said head, a slotted member juxtaposed to and revolving with the suction-head, a relatively stationary guide having a part concentric to the center of revolution of the suction-head and having its ends running off eccentrically thereto, and a form adapted to cover the suction-head and to engage the walls of the said slot in the slotted member and the said guide, the form also having a part engaging a part of said valve when the form is in position whereby to open the valve.

70 25. A machine for making paper articles, comprising a means for supplying paper-pulp, means arranged to move in and out of the pulp, and including devices for exerting a suction in the pulp, a separate foraminous form adapted to be carried with said means into the pulp and coacting with said devices for exerting a suction for the purpose specified, a carrier adapted to carry said form to and from said means for moving it in and out of the pulp, and devices for automatically disconnecting the form from and connecting it with said carrier as it moves into and out of engagement with said means for submerging the form in the pulp.

26. A machine for making paper articles comprising a vat adapted to carry paper-pulp, a revolubly-mounted means coacting with the vat and including devices for exerting a suction in the vat, a foraminous form adapted to be engaged with and disconnected from said means and to coact with said suction devices, means for engaging the form with and disengaging it from said revolubly-mounted means, 5 a carrier for moving the form to and from said revolubly-mounted means, and devices for automatically disconnecting the form from and connecting it with the carrier as said form engages and disengages said revolubly-mounted means.

10 27. A machine for making paper articles comprising the combination of a vat, suction devices including a suction-head, means for

revolubly mounting the suction devices to dip the head in and out of the vat, a foraminous 20 shape adapted to engage the suction-head, means for removably supporting the foraminous shape in engagement with the suction-head, a relatively stationary guide having a concentric intermediate portion and eccentric 25 end portions, the guide being engaged by a part on the foraminous form, and means for engaging the form with one end of the guide and disengaging it from the other end thereof.

20 In testimony whereof I have signed my name 30 to this specification in the presence of two subscribing witnesses.
